UNITED STATES PATENT OFFICE.

JOHN BECKER, OF HYDEPARK, MASSACHUSETTS, ASSIGNOR TO BECKER-BRAINARD MILLING MACHINE COMPANY, OF PORTLAND, MAINE, A CORPORATION OF MAINE.

DESIGN FOR A MILLING-MACHINE FRAME.

SPECIFICATION forming part of Design No. 35,448, dated December 17, 1901.

Application filed November 14, 1901. Serial No. 82,319. Term of patent 14 years.

To all whom it may concern:

Be it known that I, JOHN BECKER, a citizen of the United States, residing at Hydepark, in the county of Norfolk and State of Massachusetts, have invented and produced a certain new and original Design for Milling-Machine Frames; and I do hereby declare the following to be a full, clear, and exact description of the invention, such as will enable others skilled in the art to which it appertains to make and use the same.

The figure of the drawing is a perspective view of a milling-machine frame embodying my design.

As shown in the drawing, the leading and material features of my design consist of a base rectangular in plan, the upper surface of which curves downwardly at the edges of the base and upwardly to meet the lateral surfaces of a vertical column rising from the rear central portion of the base. The column is rectangularly parallelepipedal in general form. At the front of the column at the opposite edges of its front surface are two projections provided with plane vertical front surfaces lying in the same plane and with plane vertical outside lateral surfaces, which meet the front surfaces at acute angles. The lateral surfaces of the column curve toward the lateral surfaces of the projections and also curve toward each other at the top of the column, as shown. A flat vertical web projects from the front portion of the top of the column, the front surface of which is a plane continuous with the front surface of the column. The rear surface of the web flows into the upper surface of the column in graceful curves. The edges of the web converge on slightly convexly-curved lines as the web

rises from the column and are then concavely curved to meet the circular upper end of the web. At the rear the top of the column extends outwardly and upwardly, and from this outwardly and upwardly extending portion a web rises parallel with the front web and of substantially the same configuration. The rear surface of the outwardly and upwardly extending portion of the column is reversely curved to form a continuation of the rear surfaces of the column and of the rear web. The front surface of the rear web flows into the upper surface of the column, which surface rises from the front to the rear web in a concave curve and is also concavely curved transversely. A hollow cylindrical body open on its under side connects the upper ends of the webs. From each of the webs an arm of less thickness than the web extends laterally, the edges of which diverge at the base to meet the edge of the web. The free ends of the arms are circular and slightly enlarged. The circular upper ends of the webs and the circular free ends of the arms are provided with circular openings, and each of the webs is provided with a circular opening below and in vertical alinement with the upper opening.

Having thus described my invention, I claim as new and desire to secure by Letters Patent of the United States—

The design for a milling-machine frame substantially as shown and described.

In testimony whereof I affix my signature in presence of two witnesses.

JOHN BECKER.
